[57] CLAIM

The ornamental design for an electroacoustic transducer, as shown and described.

DESCRIPTION

FIG. 1 is a perspective view of the front, top and left side of an electroacoustic transducer showing our new design;

FIG. 2 is a front elevational view thereof;

FIG. 3 is a top plan view thereof;

FIG. 4 is a left side elevational view thereof, the right side being a mirror image thereof;

FIG. 5 is a bottom plan view thereof;

FIG. 6 is a rear elevational view thereof;

FIG. 7 is a perspective view of the front, top and left side of a second embodiment of FIG. 1; and,

FIG. 8 is a front elevational view of FIG. 7.

The undisclosed right, bottom and rear views of the second embodiment are identical to the corresponding views of the first embodiment.
